UNITED STATES PATENT OFFICE.

HARRY LANDSIEDEL, OF NORWOOD, OHIO, ASSIGNOR TO THE DALTON ADDING MACHINE COMPANY, OF CINCINNATI, OHIO, A CORPORATION OF OHIO.

ADDING MACHINE.

Application filed February 16, 1921. Serial No. 445,434.

To all whom it may concern:

Be it known that I, HARRY LANDSIEDEL, a citizen of the United States, residing at Norwood, Hamilton County, and State of Ohio, have invented a new and useful Adding Machine, of which the following is a specification.

This invention relates to adding machines.

An object of the invention is to provide an improvement to facilitate the use and operation of adding machines in the addition of parallel columns of numbers. In the case of an adding and listing machine the numbers are listed in parallel columns on a sheet of paper without the necessity of moving the paper or platen laterally, leaving it in a single laterally adjusted position and operating the paper feed mechanism only to feed the paper properly in line spacing.

My present invention relates specially to machines of the simplified key-board type, also known as "ten key" machines, and for convenience the invention is illustrated in a Dalton adding machine which is of the simplified "ten key" type.

Heretofore work of this character has been performed on the Dalton adding machine by striking on the key-board the item to be added in the left hand column and then setting up the correct number of ciphers to form a space between the left and right hand columns, and then striking on the key-board the item for the right hand column; although it has been unnecessary to print the ciphers between the two columns. This work involves mental concentration and effort in order to set up the correct number of ciphers between the two items so that the items will be listed in the proper denominational orders in parallel columns. The present invention overcomes this trouble and eliminates the necessity of counting the ciphers to be set up between the parallel columns and makes it possible to add two columns of items side by side without giving thought to the numerical order of the amounts to be added. This desirable and advantageous result is obtained by the provision of mechanism which renders it unnecessary to set up or strike on the key-board ciphers corresponding to the spaces between the parallel columns of items. In the use of the invention for adding items in parallel columns in machines of the Dal-

ton type an item to be added in the left hand column is first set up in the laterally movable differential mechanism; after which the differential mechanism is tabulated or shifted to the proper position to add the 60 digits of the item in their proper denominational orders. The machine is then operated to add the item, after which the item for the right hand column is set up in the differential mechanism in the usual way, and 65 added. The paper carriage is held from lateral movement and also is prevented from feeding the paper in line spacing while the item is being entered in the left hand column, so that the two items—one in the left 70 hand column and the other in the right hand column—are listed on the same line. As an incident to the adding and listing of the item in the right hand column, the platen is operated to feed the paper in line spacing 75 ready for the next items of the series.

An additional object of the invention is to provide means for controlling the paper feed mechanism in order to obtain the desired result so that items in the right and 80 left hand columns will be listed in proper alignment. For this purpose in the specific embodiment of the invention shown, the paper feed mechanism is held inoperative when the item in the left hand column is 85 listed, although the order of the operation may be varied if desired. In this connection it may be stated that an important feature of the invention comprises mechanism for feeding the paper one line space for each 90 two movements or operations of the listing mechanism.

Another object of the invention is to provide equipment for returning the machine to normal; that is, for disabling that part 95 of the present invention which causes the paper to be moved only one line space for each two operations of the machine. This result is obtained by the use of a normalizing lever which, when adjusted in one 100 position, permits the machine to be used for ordinary purposes of an adding and listing machine; and which, in another adjusted position, causes the paper to be moved a single line space for each two operations of 105 the machine.

While the present invention has been disclosed in a machine containing differential mechanism of the Dalton type, it is clear that the invention is not limited to use in 110

association with Dalton differential mechanism. Obviously, the invention may be used in connection with the differential mechanism of other machines such, for instance, 5 as the Sundstrand machine, the Moon-Hopkins machine, and Hoch machine, and others.

In the drawings Fig. 1 is a vertical longitudinal sectional view of a machine of the Dalton type having the present invention 10 incorporated therein.

Fig. 2 is a plan view of a portion of the present invention showing its relation to the differential carriage and also a part of the connections for controlling the paper 15 carriage.

Fig. 3 is a broken rear elevation showing details of the invention cooperating with the differential carriage. In this view the differential carriage is in its clear or normal 20 position.

Fig. 4 is a similar view showing the differential carriage after it has moved a number of spaces to the left.

Fig. 5 shows a specimen of the work performed by use of the present invention.

It is known that, as shown, the Dalton adding machine is of the simplified ten key-type, in which the numeral keys 1 are arranged in a convenient key-board at the 30 front of the machine. By operation of the numeral keys numbers are set up in differential mechanism 2 which is moved from order to order under control of escapement mechanism, as the keys are operated. One 35 form of such escapement mechanism is shown, the same comprising an escapement segment 3 arranged to step from order to order under control of the escapement pawls 4. The segment 3 is attached to a shaft 5 which is entrained with the carriage of the differential mechanism by a rack 6 on the shaft meshing with a rack 7 on the carriage. The specific arrangement by which the 40 levers of the keys 1 operate the universal 45 escapement bar 8 (Figs. 3 and 4) to permit the carriage to move from order to order is unimportant so far as the present invention is concerned, it being sufficient for present purposes to state that, as usual, the escapement bar 8 is operated to permit order to order movement of the carriage when the 50 numeral keys are operated.

The differential carriage contains the usual digit stops which are arranged in rows 55 in the well known manner, and which are set up by operation of the numeral keys as said keys are operated, as required to limit forward movement of the racks 9 which control the movement of the type-carriers 10. Springs 11 provide the necessary power for moving the racks and type-carriers forwardly at the proper times.

As usual, the paper is fed to the type 60 around a platen 12 which is operated to feed the paper in line spacing by the auto-

matic operation of appropriate mechanism provided in the machine for that purpose. A part of the usual actuating mechanism by which the platen is operated to feed the paper in line spacing is shown, the same 70 comprising a pawl 13 operated from a shaft 14 which is rocked at the proper time to cause the pawl 13 to engage a ratchet wheel 15 on the platen shaft, and thereby rotate the platen. An arm 16 on the shaft 14 is 75 provided with spring 17 for the purpose of actuating said arm as required to turn the shaft 14 in one direction. The line space mechanism is usual in the Dalton adding machine and requires no further description 80 herein. However, it is apparent that if the operation of the arm 16 be interfered with or prevented, the line space mechanism will be prevented from functioning. Means for interfering with or preventing operation of 85 the arm 16 when items are listed in one column is included in the present invention and is hereinafter described.

The type on the type-carriers are driven to print by operation of the usual type driving hammers 18 and the items printed are added by the adding pinions 19 which are operated by the racks 9. I now proceed to describe the present invention which cooperates with the mechanism above described. In order to list an item in the left hand column the item is first set up in the differential carriage, after which said carriage is tabulated or shifted to position the digit stops that had been set up, so that they will be in their proper denominational orders. For this purpose a tabulator or shift key 20 is provided, the same being supported near the key-board upon the end of a key lever 21. The key lever 21 is pivoted upon a support 22 and the rear end of said lever is guided in a slot 23 in a stationary plate 24. A latch plate 25 is pivoted upon the rear portion of the key lever 21 and is formed with a shoulder 26 at its lower end 105 which is arranged to effect latching engagement with a latch block 27 when the rear end of the lever 21 is raised by the depression of the key 20. For the purpose of actuating the lower end of the latch plate 25 110 toward the left relative to the operator working at the key-board of the machine (toward the right when viewed from the rear as in Figs. 3 and 4) to engage said plate upon the latch block 27, a spring 28 is provided, the same having one end connected to the lever 21 (Fig. 1) and the other end engaging the plate 25 and having a tendency to press the lower end of the plate 25 in the direction stated.

After the setting up of the desired item, the tabulator or shift key 20 is operated. Depression of the forward end of the lever 21 raises the rear end thereof and permits the latch plate 25 to effect latching engage- 130

ment with the latch block 27 in the manner stated. The latch plate 25 is immediately beneath the arm 29 of a pawl. One end of the arm 29 is pivoted to a support 30 carried by a swinging link 31, and extending through a slot 32 in the stationary plate 24. Extent of movement of the arm 29, therefore, is limited by the length of the slot 32. The arm 29 is actuated toward the right relative to the operator at the key-board of the machine (toward the left when viewed from the rear as in Figs. 3 and 4) by a spring 33 in connection with the link 31. A pawl 34 is formed on the end of the arm 29 in position to be raised into engagement with a rack 35 on the differential carriage. The arrangement is such that the carriage must be moved at least one step or space toward higher numerical orders, thus requiring at least one digit to be set up in the differential mechanism, before the rack 35 is in position to be engaged by the pawl 34. This will be readily understood by reference to Fig. 3, in which it will be seen that at least one step movement of the differential carriage is required before the pawl 34 can be engaged with the rack.

As a result of the construction described, it follows that after any item has been set up in the differential mechanism the tabulator or shift key 20 may be operated to raise the pawl 34 into engagement with the rack 35. At the same time, and as an incident to operation of the key 20, the escapement mechanism is disconnected, thus permitting the differential carriage to be moved toward higher denominational orders by the usual actuating device (not shown) a distance equal to the length of the slot 32. Obviously, movement of the differential mechanism toward higher denominational orders will be stopped when the support 30 strikes the end wall of the slot 32. This positions the differential mechanism properly so that the digits of the item set up therein will be in the proper denominational orders so that when the adding and listing mechanism of the machine are operated the item will be properly listed and added.

In order to prevent operation of the type carriers and racks in lower denominational orders so that the proper item will be listed and added when the above-described operation occurs, I provide mechanism for raising or setting up a sufficient number of zero or cipher stops to prevent operation of all the racks and type-carriers in lower denominational orders at the right of the item which is being listed in the left hand column. The usual "spilt" mechanism of the machine will prevent printing of the ciphers at the right of the item being listed, but as such split mechanism is well known and constitutes no part of the present invention the same is not described.

In order to set up zero or cipher stops for the purpose stated, I provide an arm 36 having one end pivotally supported at 37 and extending across the latch plate 25, so that when said latch plate is raised by operation of the tabulator or shift key 20, said arm 36 will be raised. The arm 36 is provided with a projecting portion 38 having a curved part 39 shaped so as to enable the zero stops to contact therewith and be raised thereby as the differential carriage moves toward higher denominational orders, as a result of the operation of the tabulator or shift key 20. Thus a sufficient number of zero stops are raised to prevent movement of all of the type-carriers and racks at the right of the item being listed and added in the left hand column.

As before mentioned, my invention includes means for disconnecting the escapement pawls 4 from the segment 3 so as to permit the differential carriage to move to position to present the set up stops in proper denominational orders, as required to cause the item to be listed and added properly in the left hand column. For this purpose the arm 36 is provided with an extended portion 40 engaging under a part of an arm 41 which is pivotally supported at 42. A projection 43 on the arm 41 engages with the universal escapement bar 8 which is connected with the escapement pawls 4 by means of a connection 44. Consequently, when the arm 36 is raised by operation of the tabulator or shift key the pawls 4 are disengaged from the segment 3, thus permitting the differential carriage to be moved the full distance required; movement of the carriage being stopped when the support 30 engages the end wall of the slot 32. After the differential carriage has been positioned in this manner it is intended that the adding and listing mechanisms of the machine be operated in the usual way, with the result that the item that had been set up in the differential mechanism will be listed and added properly in the left hand column. As an incident to such operation the differential carriage is restored to its starting point and cleared in the well understood manner.

The pawl 34 extends downwardly a sufficient distance to engage the upper end of the latch plate 25 and the force or power of the movement of the differential carriage is sufficient to overcome the power of the spring 28 and to disengage the latch plate 25 from the latch block 27, permitting the key lever 21 to return to its normal position, and the pawl 34 to drop out of engagement with the rack 35, leaving the carriage free to be returned to its starting position. When this occurs the arm 36 moves to its lower position, permitting the escapement pawls 4 to re-engage the seg-

ment 3. The machine is then ready for operation in the usual way.

As previously mentioned in this specification, the present invention includes mechanism for controlling the paper feed mechanism to prevent movement of the paper in line spacing when the machine is operated to add and list an item in the left hand column. By preventing line space movement of the paper when an item is listed in the left hand column, the paper is retained stationary so that the item listed in the right hand column will be listed in horizontal alinement with the item in the left hand column. By reference to Fig. 5 it will be seen that there are two parallel vertical columns of items separated by a noticeable space, and that the items in the two vertical columns are horizontally alined. This is the result of preventing line space operation when items are listed in the left hand column. I will now proceed to a description of the mechanism for preventing operation of the line space mechanism when an item is added or listed in the left column and which permits the paper to be moved in line spacing as an incident to the listing of the item in the right hand column.

As before mentioned the operation of the line space mechanism may be prevented by interfering with or preventing operation of the arm 16 to the extent necessary to effect operation of the line space mechanism. To limit movement of the arm 16 in order to prevent operation of the line space mechanism I provide an abutment which, as shown, is in the form of an arm 45 (Fig. 1) supported on a shaft 46 and being movable from the position shown in solid lines (in which the arm 16 is free to operate) to the position shown in dotted lines in which the arm 16 will strike the abutment and be stopped as required to prevent the line space mechanism from functioning. A link 47 connects an extension of the arm 45 with one arm of a bell crank lever 48 which is pivoted on a support 49. The other arm of the bell crank lever 48 engages in a slot in a sliding plate 50 which is supported for sliding movements near the base of the machine. The plate 50 is capable of movement in forward and rearward directions and is actuated in a rearward direction by a spring 51. A roll 52 on the plate 50 operates against a cam member 53 attached to the shaft 5 or the segment 3. The construction and arrangement are such that when the differential carriage is tabulated or shifted to a position to list an item or number in the left hand column, the roll 52 will pass from the shoulder 54 of the cam, thus permitting the spring 51 to move the plate 50 rearwardly. This rearward movement of the plate 50 draws the lower arm of the bell crank lever 48 rearwardly as a result of

which the abutment arm 45 is raised from the position shown in solid lines (Fig. 1) to the position shown in dotted lines. When the abutment arm 45 is in the position shown in dotted lines, movement of the arm 16 will be stopped thereby, thus preventing the line space mechanism from functioning. As a consequence of this the item is listed and added in the left hand column without moving the paper in line spacing.

Although the paper is not moved in line spacing when an item is listed in the left hand column, the paper is automatically moved for line spacing as an incident to the listing of the item in the right hand column. This result is obtained because when an item is listed in the right hand column the roll 52 is against the cam 53 which holds the lower arm of the lever 48 in a forward position in opposition to the power of the spring 51. When the lower arm of the lever 48 is in its forward position the abutment arm 45 is out of the path of movement of the arm 16, leaving said arm 16 free to move to operate the line spacing mechanism.

My invention also includes means for normalizing the machine by disabling the mechanism for preventing operation of the line space mechanism so as to enable the line space mechanism to operate whenever any item is listed, whether the item be listed in one column or the other. The line space mechanism will be permitted to operate if the abutment arm 45 (Fig. 1) be held out of the path of movement of the arm 16. The abutment 45 may be held out of the path of movement of the arm 16 by the construction shown. For this purpose I provide a sliding link 55 having a finger 56 arranged to engage with a shoulder 57 on the plate 50, and to hold said plate 50 in its forward position, when the link 55 is held in its forward position. The forward end of the link 55 is connected to one arm 58 of a lever which is pivoted upon a support 59. The other arm 60 of said lever extends through a slotted plate 61 conveniently arranged near the key-board of the machine. The plate 61 has a longitudinal slot 62 through which the lever arm 60 extends. A notch 63 is at the forward end of said slot and a similar notch 64 is at the rear end of said slot. The lever arm is sufficiently resilient to permit movement thereof from the notch 63 to the notch 64 and vice versa. By engaging the lever arm 60 in the notch 64 at the rear end of the slot 62, as shown, the link 55 will be retained in its rearward adjustment to permit movement of the plate 50, so that when the machine is operated to list an item in the left hand column the paper feed mechanism will be prevented from functioning as above described. However, if the lever be operated to engage the arm 60 in the forward notch 63 the link 55

55 will be moved to and retained in a forward adjustment in which the finger 56 will be engaged by the shoulder 57 on the plate 50, thereby preventing operation of the connections which disable the line space mechanism. The machine is thus normalized, so that the line space mechanism will function at each operation of the machine.

From the foregoing it is clear that my invention completely and satisfactorily obtains all of its intended purposes and objects. By use of this invention items may be listed on horizontal parallel lines in vertically parallel columns. The columns are separated by noticeable spaces so that there is no confusion in reading the different columns. By use of the improved "split" and "normal" mechanism, (by which terms reference is made to the lever 58-59 and its connections) the machine may be rendered capable for use to add and list items in the usual way, or to add and list the items in parallel columns as desired.

Obviously, the construction and arrangement of the invention may be widely varied without departure from the principle and nature thereof. I do not restrict myself to unessential features or limitations, but what I claim and desire to secure by Letters Patent, is:

1. In an adding machine, the combination with a differential carriage, and escapement mechanism controlling movement of the carriage from lower to higher denominational order positions in the machine, of a tabulating device operable to disable the escapement mechanism to permit the carriage to be moved free from the control of the escapement mechanism, an element movable by the tabulating device to engage the carriage, means in connection with said element to limit movement thereof to stop movement of the carriage, and means for restoring said element to its starting position after the carriage has been stopped thereby.

2. In an adding machine, the combination with a series of racks arranged in numerical orders, a differential carriage, denominational rows of stops arranged in said carriage, and escapement mechanism for moving said carriage step by step from lower to higher denominational orders, of a device for disabling said escapement mechanism to permit the carriage to move more than one step at a single movement, an element operated by said device to engage the carriage to stop movement of said carriage, means for returning said element to its starting position after the carriage has been stopped thereby, and means for setting up a number of the stops in the carriage as an incident to the movement thereof as aforementioned.

3. In an adding machine, the combination with a series of racks arranged in denomina-

tional orders, a differential carriage, stops arranged in denominational rows in said carriage for limiting movement of said racks, and escapement mechanism for moving said carriage step by step toward higher denominational orders and preventing said carriage from moving more than one step at a time, of a device for disabling said escapement mechanism to permit the carriage to move more than one step at a single movement, a latch for holding said device in position to disable the escapement mechanism, and means operated by the carriage for releasing said latch.

4. In an adding machine, the combination with a series of racks arranged in denominational orders, a differential carriage, stops arranged in denominational rows in said carriage for limiting movement of said racks, and escapement mechanism for moving said carriage step by step toward higher denominational orders and preventing said carriage from moving more than one step at a time, of a device for disabling said escapement mechanism to permit the carriage to move more than one step at a single movement, a latch for holding said device in position to disable the escapement mechanism, and means adjustable by said device to stop movement of said carriage.

5. In an adding machine, the combination with a series of racks arranged in denominational orders, a differential carriage, stops arranged in denominational rows in said carriage for limiting movement of said racks, and escapement mechanism for moving said carriage step by step toward higher denominational orders and preventing said carriage from moving more than one step at a time, of a device for disabling said escapement mechanism to permit the carriage to move more than one step at a single movement, a latch for holding said device in position to disable the escapement mechanism, and means adjustable by said device to stop movement of said carriage and arranged to release said latch to permit said device to return to its starting position.

6. In an adding machine, the combination with a series of racks arranged in denominational orders, a differential carriage, stops arranged in denominational orders in said carriage, and escapement mechanism for moving said carriage step by step to position the stops therein as required to limit movement of said racks, of a device for disabling said escapement mechanism to permit the carriage to move more than one step at a single movement, an element operated by said device to engage the carriage to stop movement of said carriage, a latch for holding said device in position to retain said element in engagement with the carriage, and means operated by the carriage for releasing said latch leaving said device free.

to return to its starting position and permitting said element to be disengaged from said carriage.

7. In an adding machine, the combination with a series of racks arranged in denominational orders, a differential carriage, stops arranged in denominational orders in said carriage, and escapement mechanism for moving said carriage step by step to position the stops therein as required to limit movement of said racks, of a device for disabling said escapement mechanism to permit the carriage to move more than one step at a single movement, an element operated by said device to engage the carriage to stop movement of said carriage, a latch for holding said device in position to retain said element in engagement with the carriage, means operated by the carriage for releasing said latch leaving said device free to return to its starting point and permitting said element to be disengaged from said carriage, and means for disengaging said element from said carriage and returning said element to its starting point.

8. In an adding machine, the combination with a series of racks arranged in denominational orders, a differential carriage, stops arranged in denominational orders in said carriage, and escapement mechanism for moving said carriage step by step to position the stops therein as required to limit movement of said racks, of a device for disabling said escapement mechanism to permit the carriage to move more than one step at a single movement, an element operated by said device to engage the carriage to stop movement of said carriage, a latch for holding said device in position to retain said element in engagement with the carriage, means operated by the carriage for releasing said latch leaving said device free to return to its starting point and permitting said element to be disengaged from said carriage, and means for setting up a number of the stops in the carriage as an incident to the movement of the carriage as aforesaid.

9. In an adding machine, the combination with a series of racks arranged in denominational orders, a differential carriage, stops arranged in denominational orders in said carriage, and escapement mechanism for moving said carriage step by step to position the stops therein as required to limit movement of said racks, of a device for disabling said escapement mechanism to permit the carriage to move more than one step at a single movement, an element operated by said device to engage the carriage to stop movement of said carriage, a latch for holding said device in position to retain said element in engagement with the carriage, means operated by the carriage for releasing said latch leaving said device free to return to its starting point and permitting

said element to be disengaged from said carriage, means for disengaging said element from said carriage and returning said element to its starting point, and means for setting up a number of the stops in the carriage as an incident to the movement of the carriage as aforesaid. 70

10. In an adding machine, the combination with a differential carriage, stops arranged in denominational rows in said carriage, and escapement mechanism for moving said carriage step by step toward higher denominational orders and preventing said carriage from moving more than one step at a single movement, of a device for disconnecting the escapement mechanism to permit the carriage to move more than one step at a single movement, a latch for holding the escapement mechanism disconnected, and means operated by the carriage for releasing 80 said latch.

11. In an adding machine, the combination with a differential carriage, stops arranged in denominational rows in said carriage, and escapement mechanism for moving said carriage step by step toward higher denominational orders and preventing said carriage from moving more than one step at a single movement, of a device for disconnecting the escapement mechanism to permit the carriage to move more than one step at a single movement, a latch for holding the escapement mechanism disconnected, an element adjustable by said device to stop movement of said carriage, and automatic means 90 for releasing said latch. 95

12. In an adding machine, the combination with a differential carriage, stops arranged in denominational rows in said carriage, and escapement mechanism for moving said carriage step by step toward higher denominational orders and preventing said carriage from moving more than one step at a single movement, of a device for disconnecting the escapement mechanism to permit the carriage to move more than one step at a single movement, a latch for holding the escapement mechanism disconnected, an element adjustable by said device to stop movement of said carriage, automatic means 100 for releasing said latch, and means for returning said element to its starting point when said latch is released. 110

13. In an adding machine, the combination with a differential carriage, stops arranged in denominational rows in said carriage, and escapement mechanism for moving said carriage step by step toward higher denominational orders and preventing said carriage from moving more than one step at a single movement, of a device for disconnecting the escapement mechanism to permit the carriage to move more than one step at a single movement, and an element movable by said device to engage the carriage 120 125 130

to stop movement of said carriage and to permit said escapement mechanism to become re-engaged.

14. In an adding machine, the combination with a differential carriage, stops arranged in denominational rows in said carriage, and escapement mechanism for moving said carriage step by step toward higher denominational orders and preventing said carriage from moving more than one step at a single movement, of a device for disconnecting the escapement mechanism to permit the carriage to move more than one step at a single movement, an element movable by said device to engage the carriage to stop movement of said carriage and to permit said escapement mechanism to become re-engaged, and automatic means for returning said element to its starting position after the carriage has been stopped thereby leaving the carriage under control of said escapement mechanism.

15. In an adding machine, the combination with a differential carriage, stops arranged in denominational rows in said carriage, and escapement mechanism for moving said carriage step by step toward higher denominational orders and preventing said carriage from moving more than one step at a single movement, of a device for disconnecting the escapement mechanism to permit the carriage to move more than one step at a single movement, an element movable by said device to engage the carriage to stop movement of said carriage and to permit said escapement mechanism to become re-engaged, and means for setting up a number of stops in the carriage as an incident to the movement of the carriage as afore-40 said.

16. In an adding machine, the combination with a differential carriage, stops arranged in denominational rows in said carriage, and escapement mechanism for moving said carriage step by step toward higher denominational orders and preventing said carriage from moving more than one step at a single movement, of a device for controlling the escapement mechanism to permit the carriage to move more than one step toward higher denominational orders at a single movement, a latch for holding said device in position to control the escapement mechanism as aforesaid, and an element for stopping movement of said carriage and for releasing said latch to permit said escapement mechanism to resume control of said carriage.

17. In an adding machine, the combination with a differential carriage arranged to be moved step by step toward higher denominational orders, and escapement mechanism controlling the movement of said carriage toward higher denominational orders and preventing said carriage from moving

more than one step at a single movement, of a device for controlling the escapement mechanism to permit the carriage to move more than one step at a single movement, a latch for holding said device in position to control the escapement mechanism to permit the carriage to move more than one step at a single movement, and an element for stopping movement of the carriage as aforesaid and for releasing said latch to permit the escapement mechanism to resume control of the carriage.

18. In an adding machine, the combination with a differential carriage movable toward higher denominational orders, and escapement mechanism controlling the movement of the carriage toward higher denominational orders and preventing the carriage from moving more than one denominational order at a single movement, of a device for controlling the escapement mechanism to permit the carriage to move more than one denominational order at a single movement, a latch for holding said device in position to control the escapement mechanism as aforesaid, and a stop movable by said device into engagement with the carriage to stop movement of the carriage and being movable by the carriage to position to release said latch.

19. In an adding machine, the combination with a differential carriage movable toward higher denominational orders, and escapement mechanism controlling the movement of the carriage toward higher denominational orders and preventing the carriage from moving more than one denominational order at a single movement, of a device for controlling the escapement mechanism to permit the carriage to move more than one denominational order at a single movement, a latch for holding said device in position to control the escapement mechanism as aforesaid, a stop movable by said device into engagement with the carriage to stop movement of the carriage and being movable by the carriage to position to release said latch, and automatic means for disengaging said stop from said carriage after the carriage has been stopped thereby.

20. In an adding machine, the combination with a differential carriage movable from order to order toward higher denominational orders, and escapement mechanism controlling the order to order movement of the carriage and preventing the carriage from moving more than one denominational order at a single movement, of a device for controlling said escapement mechanism to permit the carriage to move more than one denominational order at a single movement, a latch for retaining said device in position to control said escapement mechanism, a stop controlled by said device for limiting movement of said carriage, and means op-

erated as an incident to the movement of said carriage for releasing said latch to permit the escapement mechanism to resume control of said carriage.

- 5 21. In an adding machine, the combination with a differential carriage movable from order to order toward higher denominational orders, and escapement mechanism controlling the order to order movement 70
10 of the carriage and preventing the carriage from moving more than one denominational order at a single movement, of a device for controlling said escapement mechanism to permit the carriage to move more than one 75
15 denominational order at a single movement, a latch for retaining said device in position to control said escapement mechanism, a stop controlled by said device for limiting 80 movement of said carriage, means operated
20 as an incident to the movement of said carriage for releasing said latch to permit the escapement mechanism to resume control of said carriage, and automatic means for restoring said stop to its initial position.
25 22. In an adding machine, the combination with a differential carriage, and escapement mechanism controlling the order to order movement of said carriage toward higher denominational orders and preventing 85
30 said carriage from moving more than one denominational order at a single movement, of a device for controlling the escapement mechanism to permit the carriage to move more than one denominational order 90
35 at a single movement, a swinging support, a stop pivoted on said support, means for moving said stop into engagement with said carriage as an incident to the movement of 95
40 said device to control said escapement mechanism, means whereby said stop will stop the movement of said carriage, and means for disengaging said stop from said carriage to permit said escapement mechanism to resume control of said carriage.
45 23. In an adding machine, the combination with a differential carriage movable toward higher denominational orders, and escapement mechanism controlling order to order movement of said carriage toward 100
50 higher denominational orders and preventing said carriage from moving more than one denominational order at a single movement, mechanism for controlling said escapement mechanism to permit said carriage to move more than one denominational order 105
55 at a single movement, a latch for holding said last-named mechanism in position to control said escapement mechanism, and a stop for limiting movement 110
60 of said carriage and releasing said latch.
24. In an adding machine, the combination with a differential carriage movable toward higher denominational orders, and escapement mechanism controlling order to 115
65 order movement of said carriage toward higher denominational orders and preventing said carriage from moving more than one denominational order at a single movement, a latch for holding said last-named mechanism in position to control said escapement mechanism to permit said carriage to move more than one denominational order 120

27. In an adding machine, the combination with numerous recording devices arranged side by side in denominational orders

for recording on paper, and a platen operable to feed paper to the recording devices in line spacing, of mechanism for controlling different series of the recording devices to record in separated parallel vertical columns on the paper fed thereto by said platen when said series of recording devices are successively operated and while the platen remains in a single laterally adjusted position, and means operated as an incident to the operation of said mechanism for preventing line space movement of the paper when a record is made in one of said columns and permitting line space movement of the paper when a record is made in the other column.

28. In an adding machine, the combination with numerous recording devices arranged side by side in denominational orders and adapted to be operated in different series to record in separate parallel vertical columns, and a platen arranged to support paper to receive said records and to feed the paper in line spacing, of mechanism for utilizing different series of the recording devices to record in parallel vertical columns when said series of recording devices are successively operated and while the platen remains in a single laterally adjusted position, and means operated as an incident to the operation of said mechanism for preventing line space movement of the paper when a series of said recording devices is operated to record in one of said columns and permitting line space movement of the paper when a series of said recording devices is operated to record in the other column.

29. In an adding machine, the combination with numerous recording devices arranged side by side in denominational orders and adapted to be operated in different series to record in separate parallel vertical columns, and a platen arranged to support paper to receive said records and to feed the paper in line spacing, of mechanism for utilizing different series of the recording devices to record in parallel vertical columns when said series of recording devices are successively operated and while the platen remains in a single laterally adjusted position, means operated as an incident to the operation of said mechanism for preventing line space movement of the paper when a series of said recording devices is operated to record in one of said columns and permitting line space movement of the paper when a series of said recording devices is operated to record in the other column, and a device for controlling said means to permit line space movement of the paper when any series of said recording devices is operated.

30. In an adding machine, the combination with recording devices, and a platen for feeding paper in line spacing to said re-

cording devices, of differential mechanism for controlling the recording devices and being movable to different adjusted positions, and means under control of the differential mechanism for preventing line space operation of the platen when said differential mechanism is in one adjusted position and permitting line space operation of the platen when said differential mechanism is in another adjusted position.

31. In an adding machine, the combination with a platen, and means for rotating the platen in line spacing, of a differential carriage movable to different adjusted positions, and means operated as an incident to movement of said differential carriage to one adjusted position for preventing operation of the platen in line spacing.

32. In an adding machine, the combination with a platen, and means for rotating the platen in line spacing, of a differential carriage movable to different adjusted positions, and means operated as an incident to movement of said differential carriage to one adjusted position for preventing operation of the platen in line spacing and permitting operation of the platen in line spacing when the differential carriage is moved to another adjusted position.

33. In an adding machine, mechanism for feeding paper in line spacing, a differential carriage movable to different adjusted positions, and recording mechanism controlled by said carriage, in combination with means under control of said differential carriage preventing operation of the paper feed mechanism in certain adjusted positions of the differential carriage, and permitting operation of the paper feed mechanism in other adjusted positions of the differential carriage.

34. In an adding machine, mechanism operable to feed paper in line spacing, recording devices for recording on the paper, a differential carriage for controlling the recording devices, and a shaft entrained with said carriage, in combination with means operated by said shaft for preventing operation of the paper feed mechanism when said differential carriage is in certain adjusted positions and permitting operation of the paper feed mechanism when said differential carriage is in other adjusted positions.

35. In an adding machine, mechanism for feeding paper in line spacing, a differential carriage movable to different adjusted positions, and recording mechanism controlled by said carriage, in combination with means under control of said differential carriage preventing operation of the paper feed mechanism in certain adjusted positions of the differential carriage, and permitting operation of the paper feed mechanism in other adjusted positions of the differential carriage, and a device for controlling said

means to permit operation of the paper feed mechanism in any position of said carriage.

36. In an adding machine, mechanism operable to feed paper in line spacing, recording devices for recording on the paper, a differential carriage for controlling the recording devices, and a shaft entrained with said carriage, in combination with means operated by said shaft for preventing oper-

ation of the paper feed mechanism when said differential carriage is in certain adjusted positions and permitting operation of the paper feed mechanism when said differential carriage is in other adjusted positions, and a device for controlling said means to permit operation of the paper feed mechanism in any position of said carriage.

HARRY LANDSIEDEL.
